PRINTING MECHANISM FOR PRINTING A NUMBER, INCLUDING A DECIMAL FRACTION

Werner Heinze, Schwerzenbach, and Werner Julich, Wal-

lisellen, Switzerland, assignors to Precisa A. G. Rechen-

maschinenfabrik, Zurich, Switzerland, a firm

Application November 17, 1955, Serial No. 547,488

Claims priority, application Germany November 20, 1954

2 Claims. (Cl. 101—93)

Our invention relates to a printing mechanism for printing a number including a decimal fraction and, more particularly, to a printing mechanism of this kind for adding or computing machines including means for selecting the denominational position of the decimal mark.

It is an object of our invention to provide simple and efficient means for variably determining the position of the decimal point or other decimal mark to be printed coincidentally to the printing of the number.

It is a more specific object of our invention to equip a plurality of denominational units of the printing mechanism with type bars for printing decimal points, each type bar, if selected for operation, becoming effective by virtue of the momentum imparted to it by the associated digit printing lever without requiring any additional impelling means, such as springs and hammers or the like, a control element of simple construction being provided to select one of the type bars for operation thereby determining the denominational position of the decimal point.

It is a further object of our invention to provide improved means for indicating the selected position of the decimal mark.

Further objects of our invention will appear from a detailed description of a preferred embodiment thereof shown in the accompanying drawings, it being understood that such detailed description serves the purpose of illustrating the invention rather than that of restricting or limiting the same. The features of novelty will be pointed out in the claims.

In the drawings,

Fig. 1 is a transverse vertical section through the printing mechanism of a computing machine illustrating in full lines a type wheel and the associated type bar for the decimal point in retracted position and in dash-dotted lines the type wheel and the type bar in the platen striking position.

Fig. 2 is a view similar to that of Fig. 1 illustrating the platen, the type wheel and the type bar, the latter being in non-selected condition, and the other elements of the printing mechanism being omitted for sake of clarity.

Fig. 3 is a plan view of a single denominational unit of the printing mechanism shown in Fig. 1, the other denominational units being omitted for sake of clarity.

Fig. 4 is a side view of the printing mechanism shown in Fig. 1 viewed from the left, the platen, parts of the frame and all but two denominational units having been omitted for sake of clarity, and

Fig. 5 is a perspective view of the control element shown in Figs. 1, 2 and 3 and of an indicating mechanism connected therewith indicating the denominational position of the type bar selected for operation by the control element.

The printing mechanism of a computing machine shown in the drawings comprises a set of denominational units cooperating with a common paper platen 10, each unit including a mounting plate 11. The plates 11 of the set

2

are mounted on common frame rods 12 and 13 in spaced relationship, the frame rods 12 and 13 extending parallel to the platen 10 and being supported by end plates of the frame (not shown). The mounting plates 11 are held in proper spaced relationship by interposed collars 14 surrounding the rod 13 and by the engagement of the rearward ends 15 of plates 11 with vertical slots 16 provided in a vertical plate 17 forming part of the frame. Intermediate the frame rods 12 and 13 a pivot pin 18 is riveted in the mounting plate 11. A spring-impelled digit printing lever 19 is fulcrumed on the pivot pin 18, such lever having an upwardly extending arm carrying a pivot pin 20 and having a rearwardly extending arm guided in a vertical slot 21 of the frame plate 17 and connected to a helical traction spring 22 anchored to an angle bar 23 secured to plate 17. The upwardly extending arm of lever 19 is slidably guided in a slot 24 of a universal restoring bar 25 which extends across the printing mechanism parallel to the platen 10 and has end arms (not shown) pivotally mounted on pivots disposed coaxially to the pivot pins 18. A type wheel 26 is freely rotatably mounted on the pivot pin 20 and is rigidly connected with a coaxially disposed pinion 27.

Suitable means for rotatably adjusting the type wheels 26 are included in each denominational unit. In the embodiment shown in the drawings, such adjusting means are formed by a gear 28 and an actuating rack 29. The gear 28 is rotatably mounted on a pivot pin 30 secured to the printing lever 19 intermediate the pivot pins 18 and 20. The actuating rack 29 has a slot 31 slidably engaged by a frame rod 32. The rack 29 is in permanent engagement with the gear 28, the point of engagement substantially coinciding with the axis of the pivot pin 18 so that the operative engagement of the rack and the gear 28 will not be adversely affected by pivotal movement of the printing lever 19. The tip of the upwardly extending arm of the printing lever 19 is engaged by a downwardly extending lip 33 of a universal locking member 34 pivotally mounted on pivot pins 35 supported by suitable brackets (not shown) fixed to the frame of the machine. The locking member 34 is operative to lock all of the printing levers of the printing mechanism in retracted position contrary to the tendency of the springs 22.

The universal restoring bar 25 is movable by a cam (not shown) between a rearward position shown in Fig. 1 and a forward position in which it has been moved to the left and, therefore, affords liberty of movement to the printing levers 19. The printing operation is initiated by pivotal movement of the universal locking member 34 in clockwise direction causing the lip 33 to release the upper tips of the printing levers 19, whereupon the printing levers impelled by the springs 22 will rock in anti-clockwise direction moving the type wheels 26 into the dash-dotted position shown in Fig. 1 in which the selected types strike the paper on the paper platen 10 at the printing point 36 to effect the printing of a number including a decimal fraction, it being understood that the types 37 on the type wheels 26 are digit types. An ink ribbon (not shown) is disposed in front of the printing points 36.

After the printing has been effected by the impact of the type wheels on the paper platen 10, all of the type levers 19 and the type wheels mounted thereon are restored by a clockwise rocking movement of the universal restoring bar 25 returning the elements into the position shown in Fig. 1. Towards the end of their return strokes, cam faces 38 provide at the upper ends of the printing levers 19 will slide beneath the lip 33 permitting the same to snap into the position shown in Fig. 1 when the printing levers 19 reach their home positions, as shown in Fig. 1.

In this manner, the digits set up on the type wheels

26 by the racks 29 will be printed on the paper sheet placed on the paper platen 10 along the printing line.

It is the object of the present invention to provide improved means for printing the decimal mark which in the English speaking countries takes the form of a point, whereas in the European countries a comma is used for that purpose. In computing or other machines of the kind of which the present printing mechanism forms part, the necessity arises to variably elect the particular denominational digits between which the decimal mark is to be printed. For this reason, preferably each of the denominational units is provided with a printing element adapted to print the decimal mark. In the embodiment shown, this printing element takes the form of a type bar 39 fulcrumed on a pivot pin 40 riveted in the rearwardly extending arm of the printing lever 19 intermediate the pivot pin 18 and the point of attachment of spring 22. The type bar 39 is provided with a printing type 41 adapted to strike the paper platen closely at the left of printing point 36 where the type 37 of the type wheel 26 brought to effective position strikes the paper platen 10 to print a digit. The type bar 39 which is thus pivotally mounted on the printing lever 19 for movement relative thereto is adapted to be hurled against the platen to exert the printing pressure by its momentum. The type bar 39 is laterally offset at 42 (Fig. 2), whereby its upper type-carrying end is brought into a common plane with the type lever 19. Its upper end is bent rearwardly and provided with a downwardly projecting tooth 43 which engages behind an upward projection 44 disposed on the type lever 19 above the pivot pin 20. Engagement of projection 44 and tooth 43 limits the forward oscillation of the type bar 39 relative to printing lever 19. The rearward oscillation of type bar 39 relative to the printing lever 19 is limited by engagement of the end of the type bar with the rearward wall 45 of a recess provided in the upper end of printing lever 19 intermediate the pivot pin 20 and the cam face 38.

When the printing lever 19 is accelerated by the spring 22 upon disengagement of the locking member 34, the wall 45 of its recess will engage the upper end of the type bar 39 and carries the same along towards the paper platen 10. When the printing lever 19 is arrested by engagement of its type wheel with the paper platen, the type bar 39 will have reached a high speed and by virtue of its momentum will continue its rocking movement towards the paper platen until its type 41 strikes the paper platen. When the printing lever 19 is restored by the universal restoring bar 25, however, its projection 44 will engage the tooth 43 and will return the type bar 39 substantially to the position shown in Fig. 1 in which the tooth 43 may freely move between the projection 44 and the wall 45.

As a number including a decimal fraction requires the printing of but a single decimal mark, a control element is provided which is movable into the path of the type bars 39 and is adapted to obstruct the printing movement of all but a selected type bar.

For this purpose, the type bars 39 are provided with rearwardly extending heels 46 adapted to engage the control element which, in the embodiment shown, is a cylindrical element 47 which is mounted for rotation about its axis in suitable brackets (not shown) fixed to the frame of the machine, the element 47 being so disposed that engagement of its cylindrical periphery with the heels 46 of the type bars will prevent the latter from completing their printing strokes. The element 47, however, is provided with recesses 48 distributed around the periphery along a helical line so that one of the recesses 48 only at any time will register with the heel 46 of a type bar 39. Therefore, such type bar only may effect the printing of the decimal mark as has been selected for operation by a suitable angular adjustment of the cylindrical element 47.

The cylindrical element 47 is provided with a detent 75

wheel 49 cooperating with a spring-actuated detent lever 50 to be thereby resiliently adjusted to the proper angular position. A knurled knob 51 is secured to the end of the cylindrical element 47 and permits adjustment thereof to the desired position. By this adjustment the denominational position of the decimal mark may be selected as desired.

Preferably, means are provided to indicate the denominational position so selected. For this purpose, a sheave 52 is fixed to the control element 47 and an endless cord 53 guided by idle sheaves 54, 55, 56, 57 and 58 carried by suitable pivots fixed to the frame of the machine extends around the sheave 52 and has a section 59 extending parallel to a dial 60 disposed beneath a window 61 provided in the cover (not shown) of the machine. The dial 60 bears suitable marks, such as zeros, and is movable lengthwise of the window 61 in a manner well known in the computing machine art. The section 59 of the cord 53 carries a pointer 62 which extends beneath the window 61 and thus indicates the selected denominational position of the decimal mark, the numerals appearing at the right of pointer 62 representing a decimal fraction. In this manner, the indicating member 62 connected with the control element 47 by the motion-transmitting means 52, 53 indicates the desired subdivision of the number in the window 61 of the setting mechanism 63 so that in a printing operation the decimal mark will be printed at the point corresponding to the position of pointer 62.

Preparatory to the printing operation the universal restoring bar 25 is rocked in anti-clockwise direction. After the restoring bar has arrived in its uttermost rearward position, the locking member 34 is lifted to thereby release the printing levers 19 causing the springs 22 to accelerate the printing levers until the type wheels 26 strike the platen 27 thereby printing the adjusted digits along the printing line through the ribbon (not shown). As the type bars 39 are carried along by the printing levers 19, they are likewise accelerated. However, that type bar 39 only that has been selected by proper angular adjustment of the control member 47 is permitted to complete its printing stroke to print the decimal mark. The heel 46 of the selected type bar is capable of entering a recess 48 of the control member 47, whereas all of the other type bars 39 are prevented from completing their printing strokes by engagement of their heels 46 with the peripheral surface of the control elements 47. Only a single decimal mark can be printed, since the recesses 48 are so disposed that a single recess only will register at any time within a heel 46.

While the invention has been described in connection with a preferred embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as fall within the scope of the invention or the limits of the appended claims.

What we claim is:

1. A printing mechanism adapted to print a number including a decimal fraction, comprising a platen, a set of spring impelled digit printing levers, a set of type wheels, each type wheel being carried by one of said levers, means for mounting each of said levers for movement of said type wheel in a direction toward and away from a printing point on said platen, means for rotatably adjusting said type wheels, a set of printing elements adapted to print decimal marks, each element being pivotally mounted on one of said levers for relative movement thereto in said direction and adapted to be hurled against said platen by said lever to print a decimal mark adjacent said printing point, a control element common to all of said printing elements and being selectively movable into any one of a plurality of positions being opera-

tive in each of said positions to obstruct the printing movement of all but a selected one of said printing elements, an indicating member, means for movably mounting said indicating member, an indicating member dial over which said indicating member is movable, and motion transmitting means connecting said control element with said indicating member so as to enable the latter to indicate the denominational position of said selected one of said printing elements.

2. A printing mechanism adapted to print a number including a decimal fraction, comprising a platen, a set of spring impelled digit printing levers, a set of type wheels, each type wheel being carried by one of said levers, means for mounting each of said levers for movement of said type wheel in a direction toward and away from a printing point on said platen, means for rotatably adjusting said type wheels, a set of printing elements adapted to print decimal marks, each element being pivotally mounted on one of said levers for relative movement thereto in said direction and adapted to be hurled against said platen by said lever to print a decimal mark adja-

cent to said printing point, a control element common to all of said printing elements and being selectively movable into any one of a plurality of positions being operative in each of said positions to obstruct the printing movement of all but a selected one of said printing elements, said machine being provided with a window, an indicating member, means for movably mounting the latter in said window, and motion transmitting means connecting said control element with said indicating member to enable the latter to indicate the denominational position of said selected one of said printing elements.
